(57) **CLAIM**

The ornamental design for a greeting card and envelope as shown and described.

DESCRIPTION

FIG. 1 is a front perspective view of a greeting card and envelope showing my new design with the greeting card positioned fully within the envelope;

FIG. 2 is a front elevation view thereof;

FIG. 3 is a rear elevation view thereof;

FIG. 4 is a front perspective view showing my new design with the greeting card positioned partially within the envelope and partially extending from the envelope;

FIG. 5 is a front elevation view thereof;

FIG. 6 is a rear elevation view thereof;

FIG. 7 is a front perspective view showing my new design with the greeting card positioned fully outside the envelope;

FIG. 8 is a front elevation view thereof; and,

FIG. 9 is a rear elevation view thereof.

1 Claim, 9 Drawing Sheets
